UNITED STATES PATENT OFFICE.

HENRY L. GANTT, OF PAWTUCKET, RHODE ISLAND.

APPARATUS FOR TREATING CLOTH.

No. 911,560.

Specification of Letters Patent.

Patented Feb. 2, 1909.

Application filed May 6, 1907. Serial No. 371,969.

To all whom it may concern:

Be it known that I, HENRY L. GANTT, a citizen of the United States, residing at Pawtucket, county of Providence, State of Rhode Island, have invented certain Improved Apparatus for Treating Cloth, of which the following is a specification.

This invention comprises an apparatus in which may be treated, by a dyeing, bleaching or other solution, continuous lengths of cloth obtained by sewing the ends of pieces together and handling the cloth in rope form. It is particularly applicable to the treatment of cotton cloths.

15 The apparatus comprises a vertically disposed shaft communicating at the bottom with an inclined chamber or chute whose delivery end is turned or curved upward and may be parallel with the feet shaft or inclined toward it: or the chute may be curved or circular in vertical plane. The bottom of this chute is formed, so far as the support of the cloth is concerned, of a series of freely revolving rollers that extend upwardly at 20 both the receiving and delivery ends of the chute. The rollers as well as their bearings and journals are to be of suitable material to resist action of the bath with which they are in contact. They are to be independently mounted so as to individually revolve freely under stress of pressure of the cloth. Cloth introduced into the shaft or "piled" 25 therein is delivered to the receiving end of the chute and, as the pile in the shaft increases, the accumulated cloth will, by gravity, be carried around or through the chute, its travel therethrough being facilitated by the freely revolving rollers and at the place of delivery that end of the cloth rope first 30 introduced into the stack will be on top and the cloth rope may be withdrawn freely without tangling. To facilitate passage of the piled cloth from the shaft through the chute, the latter is constructed with a gradually increasing cross section from the receiving to 35 the delivery end thereof. A machine of this character can be constructed to hold any desired amount of cloth. Its size will depend upon the weight of the cloth per yard, the 40 speed at which it is moved in rope form, and the time it is to be subjected to the action of the solution while piled down in the chute. If the cloth rope is caused to travel at the 45 rate of two hundred yards per minute and it is desired to keep it piled down thirty 50 minutes, the machine should be of capacity

to hold for treatment in the chute six thousand yards and the size of the chute will depend upon the weight per yard of the cloth. The chute may be water tight and if so any 55 desired solution may be caused to continuously circulate therein. The cloth rope may be continuously piled down in the stack and continuously withdrawn from the delivery end. Every portion of the cloth in this continuous treatment will receive the same action or be subjected in the same manner and for the same length of time to the solution circulated in the chute.

Practical experience has demonstrated 60 that a machine constructed in accordance with the foregoing general description has a high efficiency and permits the continuous handling of cloth rope in the manner described without interruption of the process 65 or entanglement of the rope. I am aware that heretofore it has been proposed to construct an apparatus designed for the same general purpose with a feeding shaft, a vertical curved circular chute, the bottom of 70 which is formed by an endless power driven slatted belt but I have determined by experience that such an apparatus is incapable 75 of handling cloth in the practical, satisfactory and efficient manner in which it may be 80 handled with the apparatus disclosed herein.

In the accompanying drawings; Figure 1 is a vertical longitudinal section through one form of the apparatus; Fig. 2, a horizontal section on the line 2, 2, of Fig. 1; Fig. 3, a 85 vertical longitudinal section through another form of the apparatus; Fig. 4, a transverse section therethrough on the line 4, 4, of Fig. 3; and Fig. 5, a transverse section on the line 5, 5, of Fig. 3.

The feed shaft A of any appropriate construction, is vertically disposed and of a height suitable for the quantity or weight of cloth that is to travel through the chute. In Fig. 1, the chute B is curved in vertical 90 plane and may be square or rectangular in cross section. Its cross sectional area increases from the entrance or feed end b to the delivery or exit end c. The bottom of the chute over which the cloth travels is 95 formed by a series of transversely arranged freely revolving rollers D whose journals are mounted in suitable bearing blocks d as indicated in Fig. 5. This series of closely placed independently revolving rollers is 100 carried well up towards the shaft at the feed end and also toward the delivery end of the 105 110

chute, the design being that the rollers shall be so placed that the gravity thrust of the cloth piled down in the stack shall be facilitated in causing the passage of the pile through the chute from the feed end to the delivery end where the end of the cloth rope first introduced to the stack will be on top.

The apparatus may be constructed of timber. The rollers may be of wood or some suitable composition. It is entirely feasible that the rollers, their journals and the journal boxes be all constructed of wood.

In Figs. 3 and 4, the construction is practically the same except that the chute instead of being curved or circular in vertical plane is curved at the receiving end; then inclined; and, towards the delivery end, curved upwardly and inwardly so that the central axis of the delivery opening, if prolonged, would intersect a line passing through the axis of the stack. The purpose of such inclination of the delivery end of the chute is to cause the piled fabric as it rises to fall inwardly toward the shaft and thereby facilitate the continuous withdrawal of the cloth rope. When the apparatus is so constructed, I prefer that the inner curved wall of this portion of the chute be also supplied with a series of rollers D.

If the casing forming or inclosing the chute be water-tight it may have a supply-pipe E and a discharge-pipe F for circulation of a solution. However, the fabric piled down in the shaft may be saturated and there need be, for some purposes, no special or free bath in the chute.

The sides of the shaft A may be formed wholly or partly of vertical slats with intervening spaces as shown in the drawings.

Figs. 1 and 2 taken together and Figs. 3 and 4 taken together show that in the respective styles of apparatus therein illustrated the cross sectional area of the stack is less than that of the contiguous receiving end of the chute; and that the chute increases in cross sectional area as the delivery end thereof is approached. This facilitates free passage of the cloth pile from the stack into and through the chute. The pile formed by the single cloth rope laid down into the stack is supported by the walls of the stack and by them directed into the receiving end of the chute. The cross sectional area of the stack in each instance should be such that the cloth rope piled or laid down in it should progressively substantially fill it. Where the rope is thick, as when composed of heavy cloth the cross sectional area of the stack may be greater than when the rope is thin.

I claim:

1. In an apparatus for treating cloth in rope form, a piling-down stack, a chute having two upwardly turned ends with one of which the stack communicates and from the other of which the cloth rope is withdrawn

and having its bottom provided with a series of closely placed independent freely revolving rollers that assist the passage of the piled down fabric through the chute under the gravity stress of the pile.

2. Apparatus for treating cloth in rope form comprising a chute with two upwardly turned ends and a piling stack communicating with one end, the chute having its bottom and outer end walls provided with a series of closely placed independently freely revolving rollers so placed as to receive the greatest pressure exerted by reason of the gravity of the cloth piled down in the stack.

3. Apparatus for treating cloth in rope form comprising a stack, a chute having two upwardly turned ends with one of which the stack communicates such chute being constructed as follows,—downwardly curved from the stack, then inclined in a substantially straight line, then upwardly curved to the delivery end, the bottom portion or lower wall of the downwardly curved part, the straight inclined part and the upwardly curved part being provided with a series of independently freely revolving rollers that receive the gravity thrust of the fabric piled in the stack and facilitate passage of the piled fabric through the chute.

4. Apparatus for treating cloth in rope form comprising a stack, a chute having an upturned feed end with which the stack communicates and an upturned delivery end inclined toward the stack, the chute being provided with closely placed independently freely revolving rolls adapted to receive the gravity thrust of the cloth piled into the stack and facilitate passage of the piled cloth through the chute.

5. Apparatus for treating cloth in rope form comprising a piling-down stack, a chute having two upwardly turned ends with one of which the stack communicates and from the other of which the cloth rope is withdrawn, the stack being of less cross sectional area than the end of the chute with which it communicates and the chute having its bottom provided with a series of closely placed independent freely revolving rollers that assist the passage of the piled down fabric through the chute under the gravity stress of the pile.

6. Apparatus for treating cloth in rope form comprising a piling-down stack, a chute having two upwardly turned ends with one of which the stack communicates and from the other of which the cloth rope is withdrawn, the stack being of less cross sectional area than the end of the chute with which it communicates and the chute being of increasing cross sectional area from the receiving to the delivery end thereof and having its bottom provided with a series of closely placed independent freely revolving rollers that assist the passage of the piled

down fabric through the chute under the gravity stress of the pile.

7. In an apparatus for treating cloth in rope form, a piling down stack of such cross sectional area as to adapt it to be progressively filled by single cloth rope piled down therein, a chute having two upwardly turned ends with one of which the stack communicates and from the other of which the cloth

10 rope is withdrawn and having its bottom

provided with a series of closely placed independent freely revolving rollers that assist the passage of the piled down fabric through the chute under the gravity stress of the pile.

In testimony whereof, I have hereunto 15
subscribed my name.

HENRY L. GANTT.
